(57) **CLAIM**

The ornamental design for an improved latching mechanism, as shown and described.

DESCRIPTION

FIG. 1 is a perspective view of a latching mechanism showing our new design, with the latching aspect shown in an extended position;

FIG. 2 is a perspective view thereof, with the latching aspect shown in normal position;

FIG. 3 is a top plan view thereof;

FIG. 4 is a right side elevational view thereof;

FIG. 5 is a rear elevational view thereof;

FIG. 6 is a left side elevational view thereof; and,

FIG. 7 is a front elevational view thereof.

The broken lines environment is for illustrative purpose and forms no part of the claimed design. The broken lines environment is not shown in FIGS. 5-7 for clarity.
